DOROTHY SNOW BRUSH AND ABBOTT P. BRUSH, OF GREENWICH, CONNECTICUT.

CIGARETTE LIGHTER.

Application filed November 26, 1926. Serial No. 150,674.

The present invention is a cigarette lighter for use in automobiles and other vehicles. The jarring movements of such vehicles frequently cause the lighters, as now constructed, to break and spoil the cigarettes as they are being lighted.

The objects of this invention are to overcome this common fault of the present lighters and to provide a simple, practical form of device which will light the cigarette without injuring the same, despite the jarring, bumping or swaying of the vehicle.

These objects are attained in part by mounting the lighter element which is engaged by the cigarette in a resiliently "floated" relation so that in use it may yield instantly to the cigarette under pressure less than that which would break or injure the cigarette.

20 In the accompanying drawing forming part of this specification one practical embodiment of the invention is illustrated, but it should be understood that the invention may be embodied in various forms of structure without departure from the true and intended scope of the invention as expressed in the following specification and claims.

Figure 1 in the drawing is a general view, illustrating the use of the lighter, the casing of the device being shown partly broken away to illustrate the action.

Figure 2 is an enlarged longitudinal sectional view of the lighter.

35 Figure 3 is a cross sectional view of the device on line 3—3 of Figure 2.

Figure 4 is a sectional view of a slight modification. Figure 5 is a detached detail view of the cord grip disc.

40 The lighter element is shown as a disc or body 3 of insulating material, such as lava carrying an exposed resistance wire or ribbon 4.

In the illustration this element is loosely guided in a casing 5 which forms both a protective sheath and part of a handle for the use of the device.

The lighter element is resiliently supported in the present disclosure by a light spiral spring 6 operating freely in the casing and engaging an annular groove or shoulder 7 in the back of the lava.

55 The outward movement of the lava tip is governed in the present illustration by a flange 8 turned inwardly at the outer end

of the casing and the spring is supported at the back by an insulating base shown in the form of a plug 9 secured by a screw or screws 10 in position closing the rear end 60 of the casing. This base is shown as carrying terminals 11 inside the case for the wires of the cable 12 which carry the current to the lighter, said terminals being of a type to hold the wires securely and to enable the cable to be pulled out as far as 65 needed, without possibility of loosening or interrupting the electrical connections.

The current is led to the lighter head by connections of a flexible or resilient nature, capable of carrying the necessary amount 70 of current and at the same time sufficiently yielding to accommodate the free "floating" movements of the head. These connections are shown as two spring wires 13 projecting inwardly from the terminals on the base 75 slidingly engaged by spring brushes 14 projecting from the back of the head and having grooved or recessed end portions 15 slidingly engaged about the wires or rods 13. This construction affords a free moving 80 telescopic form of connection capable of carrying the current and adapted to guide the head without materially retarding the in-and-out movements of the same. The sliding of the brushes over the contact posts 85 keeps the contact surfaces clean and adapted to carry the current without arcing or appreciable resistance.

With this invention it will be seen that the breaking or injury of cigarettes in the course of lighting is entirely avoided because the lighter head will automatically accommodate itself to the varying movements of the person holding the lighter and that no care is necessary in placing the 90 lighter against the cigarette as the lighter will immediately yield to the cigarette, even though forcibly applied thereto.

The switch for controlling the lighting circuit may be carried by the lighter, be interposed at some point in the cord or be mounted in the reel on which the cord is ordinarily wound, but this circuit controlling switch is mechanically independent of the lighter head because the circuit to the lighter head is complete independently of the varying movements or the varying pressure on the lighter head. The lighter head is protected in its floating movements by its mounting in the casing, which latter acts 100 105 110 115 119

also as a guard protecting the user from contact with the heater element and as a shield for warding off the wind.

The range of free resiliency of the lighter head may be an inch or more or even approximating the length of the cigarette and the head yields readily to the cigarette within such range of yieldability so that injury to the cigarette is practically impossible, even though not presented squarely to the face of the lighter.

Figure 4 shows how the structure may be modified to use the wires of the cable also as the flexible connections to the lava tip. In such a case the cord is clamped at the base of the device in a suitable cord grip 16 and for the sake of increased flexibility, the wires are separated inside the case and extend separately to the two terminals at the back of the heating element.

The cord grip is shown as a flat disc overlying a knot tied in the wires at the inside of the base and having lugs 17 projecting through slots 18 in the annular wall 19 into position for engagement by the end of the spring 6. This annular wall forms a guide over which the end coils of the spring are slipped and also provides inside it a pocket for the cord grip disc which may fit relatively closely therein, it being notched at 20 at diametrically opposite points for the separated wires of the cable.

What is claimed is:

1. A cigarette lighter comprising an electric lighter head, a casing in which said head is freely movable, means for resiliently supporting said head in the casing with a sufficient range of movement and sufficiently yieldable within said range to prevent the breaking of a cigarette held against said head and means for completing the circuit to said head in all positions throughout its range of yieldability.

2. A cigarette lighter comprising an electric heater element, a holder for the same,

means for yieldingly supporting said element on said holder with a range and freedom of movement sufficient to prevent breakage of a cigarette held thereagainst and means for completing the heating circuit to said element throughout its entire range of yieldability.

3. A cigarette lighter comprising a tubular casing, an insulating base closing the rear end of said casing, an electric heater element freely movable in said casing, spring means between the base and head for supporting the head in lightly yieldable relation within the casing and means freely yieldable to the movements of said head for completing the heating circuit thereto throughout the range of its yieldability.

4. A cigarette lighter comprising a tubular casing, an insulating base closing the rear end of said casing, an electric heater element freely movable in said casing, spring means between the base and head for supporting the head in lightly yieldable relation within the casing and means freely yieldable to the movements of said head for completing the heating circuit thereto throughout the range of its yieldability, the casing having a stop at the forward end of the same limiting the outward movement of the lighter head and means for detachably securing the base in the rear end of the casing with the head positioned to engage the stop.

5. A cigarette lighter comprising a casing, a cord grip in said casing, a lighter element resiliently supported in said casing and a flexible cord entered in said casing, said cord having a portion of the same held in said cord grip and having separated flexible wires extending from the cord grip to the lighter element.

In witness whereof, we have hereunto set our hands this 23rd day of November, 1926.

DOROTHY SNOW BRUSH.
ABBOTT P. BRUSH.
